UNITED STATES PATENT OFFICE

123,838

DESIGN FOR A JEWELRY BOX OR SIMILAR ARTICLE

Jesse Mautner, New York, N. Y.

Application October 29, 1940, Serial No. 96,161

Term of patent 3½ years

To all whom it may concern:

Be it known that I, Jesse Mautner, a citizen of the United States of America, residing in New York city, county of New York and State of New York, have invented a new, original, and ornamental Design for a Jewelry Box or Similar Article, of which the following is a specification, reference being had to the accompanying drawing, forming part thereof, where- in,

I claim:

The ornamental design for a jewelry box or similar article, substantially as shown.

JESSE MAUTNER.
